Primary Examiner — Freda S Nunn*(74) Attorney, Agent, or Firm* — Staas & Halsey LLP(57) **CLAIM**

The ornamental design for a keyboard, as shown and described.

DESCRIPTION

FIG. 1 is a perspective view of front, top and right side of a keyboard showing our new design;

FIG. 2 is a perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing a state that a tablet-attaching-part is closed;

FIG. 10 is a perspective view thereof showing a state that a tablet-attaching-part is closed;

FIG. 11 is a perspective view thereof showing a state that a tablet is attached;

FIG. 12 is a perspective view thereof showing a state that a tablet is attached;

FIG. 13 is a perspective view thereof showing a state that a tablet is attached and closed; and,

FIG. 14 is a perspective view thereof showing a state that a tablet is attached and closed.

The broken lines shown are included for the purpose of illustrating the unclaimed portions of a keyboard and form no part of the claimed design.
